UNITED STATES PATENT OFFICE.

EMIL STEFFENS, OF NEW YORK, N. Y.

DESIGN FOR A PATTERN FOR CIGAR-BOXES.

SPECIFICATION forming part of Design No. 25,289, dated March 24, 1896.

Application filed January 23, 1896. Serial No. 576,605. Term of patent 14 years.

To all whom it may concern:

Be it known that I, EMIL STEFFENS, a citizen of the United States, and a resident of New York city, in the county of New York and State of New York, have invented a certain new and original Ornamental Pattern for Cigar-Boxes, &c., of which the following is a specification.

The design is illustrated in the accompanying drawing, forming part of this specification.

The design comprises a central panel of symmetrical shape, is narrower at the ends than at the center, and is placed on a background composed of a second panel having triangles at its rectangular ends. There are ornamental stars in the corners of the rectangular part of the said second panel. The points of the triangles extend to the outer border of the design. The central and the second panels are placed on a third panel of rectangular shape with indented corners. This

third panel is rayed from the center. The outer border is ornamental work, and at the corners are four rectangular designs, one of which contains triform ornamentation. In the spaces between the sides and ends of the third panel, the triangles, the outer border, and the corner rectangular work is ornamental or decorative scroll-like work. I remark also that the sides and ends of the central panel are provided with triform ornamental work.

What I claim is—

The design for an ornamental pattern for cigar-boxes, substantially as shown.

Signed at New York, in the county of New York and State of New York, this 15th day of January, A. D. 1896.

EMIL STEFFENS.
